US00D995790S

(12) **United States Design Patent** (10) **Patent No.:** **US D995,790 S**
(45) **Date of Patent:** **** Aug. 15, 2023**

(54) **ROBOTIC SURGICAL TOOL**

(71) Applicant: **DePuy Ireland Unlimited Company**,
Ringaskiddy (IE)

(72) Inventors: **Yuji Ikeda**, New Providence, NJ (US);
Anthony Di Bitonto, Brooklyn, NY (US); **Hervé Christian Claude Collet**, Jupiter, FL (US); **Elie Fournier**, Sassenage (FR)

(73) Assignee: **DEPUY IRELAND UNLIMITED COMPANY**, Ringaskiddy (IE)

(**) Term: **15 Years**

(21) Appl. No.: **29/729,800**

(22) Filed: **Mar. 30, 2020**

(57) **CLAIM**

We claim the ornamental design for a robotic surgical tool, as shown and described.

DESCRIPTION

FIG. 1 is a front perspective view of a robotic surgical tool; FIG. 2 is a rear perspective view of the robotic surgical tool of FIG. 1;

FIG. 3 is a top view of the robotic surgical tool of FIG. 1; FIG. 4 is a bottom view of the robotic surgical tool of FIG. 1;

FIG. 5 is a rear view of the robotic surgical tool of FIG. 1; FIG. 6 is a front view of the robotic surgical tool of FIG. 1; FIG. 7 is a left-side view of the robotic surgical tool of FIG. 1; and,

FIG. 8 is a right-side view of the robotic surgical tool of FIG. 1.

Any features shown in broken lines depict environmental subject matter only and form no part of the claimed design.
